ANTENNA ARRAY

Kurt Fränz, Berlin-Charlottenburg, Germany, assignor to Telefunken Gesellschaft für Drahtlose Telegraphie m. b. H., Berlin, Germany, a corporation of Germany

Application April 6, 1938, Serial No. 200,370
In Germany February 20, 1937

3 Claims. (Cl. 250—11)

This invention relates to the method of and means for reducing the undesired horizontally polarized field components of a beacon antenna system, and has for its object the provision of an improved arrangement designed to reduce the horizontal component of the waves radiated from beacon aerials having reflectors by producing an additionally radiated compensating horizontal component by inclining or sloping the reflector dipoles.

This invention will be better understood from the following description when considered in connection with the accompanying drawing. Its scope is indicated by the appended claims.

Referring to the drawing, Figure 1 shows a standard beacon arrangement having two reflectors; Figure 2 illustrates how the standard arrangement is altered in accordance with one embodiment of this invention; and Figure 3 illustrates an alternative modification of this invention.

Referring to the drawing, Fig. 1 shows a standard beacon aerial which comprises a vertical median radiator A and two reflector radiators B and C which are also mounted in vertical position in symmetric relation to A. The entire assembly is mounted over a horizontal flat metal surface D of limited dimensions as known, for instance, from vehicle antennae and the like. E is to denote the surface of the earth. If, then the vertical and the horizontal radiation components be measured in the direction of the beacon course (median perpendicular to the plane laid through the radiators), there results an undesirable horizontally polarized radiation in addition to the desired vertical component due to currents which are induced in the horizontal metal body D of the vehicle.

Now, the said horizontal component according to this invention is compensated by sloping or inclining the reflectors B and C as shown in Fig. 2. The inclination of the said two reflectors is preferably symmetric to the median radiator, in other words, in such a way that the two reflectors, viewed from the median radiator, are both inclined either outwardly or inwardly, in a way as illustrated in Figs. 2 and 3, respectively.

Actual tests made with beam or beacon aerials

of this nature have proved that the disturbing horizontal component attains a minimum value for a definite angle of inclination of the reflectors. In fact, the angle of inclination is suitably so chosen that the minimum of the horizontal component comes to lie in the horizontal plane and in the direction of the beacon course. Still, it may be advantageous to keep the minimum under a certain angle of elevation, for instance, for aerial navigation, and this end is attainable by choosing another angle of inclination for the reflectors. For instance, an outward angle of inclination of 5 degrees has proved suitable.

In the practical application of the idea underlying the invention it has proved convenient to mount the reflector radiators pivotally so that readjustment is feasible at any desired time.

I claim as my invention:

1. A device of the character described which includes a radiating antenna mounted substantially perpendicular to a conducting surface, induced currents in said surface causing undesired radiation components which are polarized in the plane of said surface, and a reflecting antenna mounted adjacent said radiating antenna and at that angle to said surface and said radiating antenna which minimizes said undesired components.

2. A device of the character described which includes a radiating antenna mounted substantially perpendicular to, and adjacent a conducting surface, means for energizing said antenna to produce a radiation field of a desired polarization, said field also causing induced currents to flow in said surface, and a pair of reflecting antennas mounted at an angle to said surface and said radiating antenna, said angle being such that a radiation field is generated having a component polarized in the plane of said surface which neutralizes the radiation field due to said induced currents.

3. A device of the character described in claim 2 in which the angle of said reflecting antenna is such that the radiation component of said reflecting antenna polarized in the plane of said surface is equal and opposite to the radiation component produced by said induced currents.

KURT FRÄNZ.
